TRIMMER FOR BOAT LOADING APPARATUS.

FILED FEB. 16, 1921.

3 SHEETS—SHEET 3.

UNITED STATES PATENT OFFICE.

ARTHUR F. CASE, OF CLEVELAND, OHIO, ASSIGNOR TO THE WELLMAN-SEAVIER-MORGAN COMPANY, OF CLEVELAND, OHIO, A CORPORATION OF OHIO.

TRIMMER FOR BOAT-LOADING APPARATUS.

Application filed February 16, 1921. Serial No. 445,494.

To all whom it may concern:

Be it known that I, ARTHUR F. CASE, a citizen of the United States, residing at Cleveland, in the county of Cuyahoga and State of Ohio, have invented a certain new and useful Improvement in Trimmers for Boat-Loading Apparatus, of which the following is a full, clear, and exact description.

10 This invention relates to trimmers for boat loading apparatus, and has for its object to provide an improved form of trimmer having the features of efficiency, durability and simplicity of construction.

15 Further the invention aims to provide a trimmer which is adapted to be attached to the lower end of a delivery chute and composed of a horizontally rotatable elbow and a vertically swinging delivery conveyor, 20 with the parts so constructed and controlled that coal or other material being loaded can be evenly distributed about the boat hatch.

The invention may be briefly summarized 25 as consisting in certain novel details of construction, and combinations and arrangements of parts which will be described in the specification and set forth in the appended claims.

30 In the accompanying sheets of drawings wherein I have shown an embodiment of the invention which operates with high efficiency, Fig. 1 is a side view of my improved trimmer; Fig. 2 is a detail sectional view illustrating the manner of rotatably supporting the trimmer from a casting at the bottom of the delivery chute; Fig. 3 is a view of the trimmer looking toward the left end of Fig. 1; Fig. 4 is a sectional view substantially along the line 4-4 of Fig. 1 looking in the direction indicated by the arrows; and Fig. 5 is a section substantially along the line 5-5 of Fig. 1 looking in the direction indicated by the arrows.

45 My improved trimmer is adapted to be secured to the lower casting 10 of a telescopic delivery chute 11, the extreme lower end of which is shown in Fig. 1. This delivery chute, which is adapted to be extended or collapsed and to be inserted into the hatch of a boat may be carried by any suitable apparatus such as a car dumper or tower, and material may be delivered to the

upper end of the chute in any suitable manner.

55 Rotatably supported by the casting 10, and adapted to turn or rotate about the axis of the upright chute 11 is a second casting 12. In this instance the lower part of the casting 10 has a laterally extending flange 10^a, to the lower face of which the upper flanged portion 12^a of the lower casting is held by a slip ring 13 and vertical bolts 14 passing through the ring and through the flange 12^a. Likewise clamped 60 between the ring 13 and the flange 12^a outwardly of the flange 10^a of the upper casting is a gear 15, which is utilized in rotating the trimmer, this gear by the clamping means shown being rotated with the casting 12 as well as with the other parts of the trimmer supported by the latter.

65 The trimmer is rotated about the axis of the delivery chute 11 by a motor 16 which is supported on the top casting 10. This motor 70 through worm gearing indicated at 17, drives a pinion 18 which meshes with the relatively large gear 15. The motor 16 is reversible, and therefore may rotate the trimmer in either direction so as to distribute the coal in all directions.

75 Secured to the lower part of the casting 12 is a delivery elbow 19 adapted to divert the coal laterally. This elbow has parallel sides, an open front facing in a direction 80 at right angles to the axis of the delivery chute 11, and a curved or rounded bottom and back wall. As the coal passing downwardly through the chute 11 and through the upper castings 10 and 12 strikes the 85 curved bottom of this elbow it is diverted laterally at substantially right angles to its direction of travel down the chute.

90 In connection with this elbow I provide an adjustable delivery member which is provided with a delivery belt, and is adapted to feed or impel the coal laterally at various elevations, and is also adapted to be swung to a position such that the coal will be delivered by the elbow 19 independently of the 95 belt so as to allow the coal to be deposited at a point more or less near the elbow.

100 The delivery member is adapted to swing about the axis of a horizontal hinge pin 20, and it is supported from this hinge pin by 105 two parallel arms 21 composed of plates

stiffened by angles, which arms are adapted to be swung alongside the parallel sides of the elbow 19. This delivery member includes a pair of guide walls 22, which extend forwardly from the arms 21, so as to act like a trough in guiding the coal passing outwardly from the mouth of the elbow, and at the bottom of these guide walls is a delivery belt 23 carried by a pair of drums 24 and 25, rotatably supported by relatively adjustable bearings 26 and 27 which are mounted on the lower supporting part 28 of the delivery member. The distance between these drums can be varied by adjustable spacers 29 to vary the tension of the belt or take up slack therein.

In Fig. 1 the delivery member is in its forwardmost position, in which position the rear part of the belt is just behind the lower discharge edge of the elbow, and since the axis of movement of the delivery member coincides substantially with the axis of curvature of the curved bottom and rear wall of the elbow, as the delivery member is swung back, the top leg of the belt will swing back of the curved wall of the elbow, and when the delivery member has been swung back to its rearmost position, the drums assume the dotted line position indicated at 24^a and 25^a, at which time the coal as it is discharged by gravity from the elbow passes clear of the belt and is neither impelled nor deflected thereby.

The belt is driven by a motor 30 which is supported at the lower rear part of the delivery member beneath the curved bottom and rear wall of the elbow, and behind the discharge face thereof. This motor is connected by a chain indicated at 31 to the shaft supporting the rear conveyor drum 24, the chain being enclosed in a guard 32.

It will be observed by reference to Figs. 4 and 5 that the top leg of the belt is quite close to the bottom of the two guide walls 22 which extend above the belt, the width of the belt being somewhat greater than the distance between the lower parallel portions of these guide walls. Notwithstanding this, there exists the possibility that part of the coal traveling forwardly with the belt may pass underneath the guide plates or walls 22 and drop from the sides of the belt. There is a possibility also, that part of this coal might, unless means were provided to prevent it, drop onto the lower rearwardly traveling leg of the belt. This would be very objectionable as it would have a tendency to injure the belt and decrease the efficiency of the belt in delivering the coal, and to avoid it I provide between the upper and lower legs of the belt a V-shaped deflector 33 (see Figs. 1 and 5) composed of two relatively adjustable or telescopic V-shaped plates the edge or apex of the V being centrally of the side edges of the belt,

some distance below the top leg thereof, and inclined downwardly and laterally beyond the edges of the lower leg of the belt so that any coal dropping off the sides of the belt and tending to lodge on the lower leg of the belt will be deflected outwardly and drop from the delivery member, the sides of which opposite the belt are open. This deflector and belt protector extends out and down to the sides of the lower part 28 of the delivery member and is bolted thereto. It is composed of two telescopic V-shaped plates to allow for the adjustment of the space between the drums which carry the belt.

The fact that the guide walls 22 extend down substantially to, but not past the top leg of the belt as shown in Figs. 4 and 5, and that the delivery member is open opposite the belt has important advantages. By terminating the guide walls 22 just above the belt there is far less liability of coal being wedged between the edges of the belt and the guide walls than would be the case if the guide walls extended downward and beyond the top leg of the belt, and in consequence with the present construction there is far less liability of the edges of the belt being cut and worn than would otherwise be the case. Furthermore, by terminating the guide walls just above the belt and by leaving the sides of the delivery member open, the belt can be removed when desired, without removing the drums. To remove the belt it is simply necessary to slacken up slightly on the bearings for the drums, remove the bearings on one side and slip the belt outwardly. This admits of a much more convenient replacement of the belt than would be possible with a delivery member closed opposite the belt.

According to another important feature of the invention, the motor 30 which drives the delivery belt is utilized to swing the delivery member about its horizontal axis of movement. To this end the shaft of motor 30 is connected by a flexible coupling indicated at 34 in Fig. 3 to a shaft 35 which extends laterally from the delivery member on the side opposite to that having the sprockets and driving chain 31. The projecting end of this shaft is provided with a pair of bevel gears 36, either of which is adapted to be clutched to the shaft by a shiftable clutch element 37 which is controlled by a lever 38, and normally held by a latch 39 in neutral position. These bevel gears 36 are adapted to rotate a bevel pinion 40 at the bottom of an upwardly extending shaft 41 which is connected by worm gearing indicated at 42 to a shaft 43 extending horizontally across the back of the elbow. This shaft carries pinions 44 which engage a pair of curved racks 45 secured to the rear

curved part of the elbow 19, and preferably to curved angles 46 secured to the parallel sides of the elbow adjacent the rear and bottom curved wall.

- 5 It will be seen, therefore, that when the shaft 43 is rotated, the pinions 44 will travel up or down the racks 45, depending upon the direction in which the shaft 43 is rotated, and when this is done the delivery 10 member as a whole is swung about its horizontal axis of movement so as to vary the angle of discharge of the belt, or to swing the latter entirely out of reach of the coal passing from the elbow. To shift the delivery 15 member in the manner above stated, the motor 30 will be temporarily stopped until the movable clutch member has been shifted into engagement with the proper bevel gear 36, and then the motor will be 20 again started, and when the delivery member has been swung to the proper position, the clutch member 37 is thrown out and the lever 38 returned to neutral position. The delivery member will be held in that position, due to the fact that the worm gearing 25 42 is self-locking gearing.

In connection with the mechanism explained above, I have made provision for automatically throwing out the clutch when the delivery member has been swung by the motor to its upper and rearmost position, and when it has been swung to its downward and forwardmost position. This is attained by providing on the curved back 30 of the elbow two limit lugs 47 and 48 (see Fig. 3), and by providing a device suitably connected to the lever 38 and positioned so as to be engaged by the lugs 47 and 48 so as to shift the lever to neutral position and 35 thus throw out the clutch when the delivery member reaches the limits of its movement. In this instance the device which is adapted to be engaged by the lugs 47 and 48 is a bell-crank 49, pivotally supported at 50 on the delivery member, and connected by a 40 link 51 to the lever 38.

When it is desired to shift the delivery member to inactive position the lever 38 is moved to the right as viewed in Fig. 3, causing the clutch member 37 to be shifted into engagement with the right hand bevel gear 36. This swings the arm 49^a of the bell-crank to a position such that when the end 45 of the arm engages the lug 47 it is cammed outward and the resulting movement of the bell-crank and link 51 shifts the lever back to neutral position, thus instantly stopping further movement of the delivery member when it is swung to its upper and rearmost 50 position. When it is desired to swing the delivery member from inactive position to the position shown in Fig. 1, the hand lever is shifted in the reverse direction from neutral position. This swings the bell-crank 55 arm 49^a to a position such that when the

delivery member has reached its forwardmost position the arm 49^a of the bell-crank is cammed inward, and this restores the lever to neutral position and disengages the clutch.

Of course the clutch can be thrown out by hand when the delivery member reaches any desired position within the range of its swinging movement, but the mechanism just described, which provides for automatically throwing out the clutch when the delivery member is in either of its extreme positions constitutes a safety feature which eliminates liability of danger to the apparatus due to inattention or lack of skill on the part of the operator.

Having described my invention, I claim:

1. In a boat loading apparatus, a trimmer comprising a rotatably supported member having a delivery conveyor for delivering material laterally of the trimmer, said conveyor comprising a belt and a pair of drums about which the belt passes, the upper leg of the belt being unsupported between the drums, and means for preventing the deposit 85 of any material on the lower leg of the belt for substantially the entire length thereof.

2. In a boat loading apparatus, a trimmer comprising a rotatably supported member with a delivery part including a pair of 90 guide walls, a delivery belt between the same and a pair of drums about which the belt passes, in combination with a deflector supported between the upper and lower legs of the belt for substantially the full distance 100 between the drums for preventing any of the material being discharged by the belt dropping onto the lower leg thereof.

3. A trimmer for a boat loading apparatus comprising a rotatable elbow and a 105 swinging delivery member supported thereby, including guide walls, a delivery belt extending between the same for discharging material in a lateral direction and at various elevations and a pair of drums about 110 which the belt passes, in combination with a diverting shield arranged between the upper and lower legs of the belt and extending for substantially the full distance between the drums for preventing material dropping 115 from the upper leg onto the lower leg of the belt.

4. A trimmer for boat loading apparatus comprising a rotatable elbow, a delivery member hinged thereto so as to swing vertically, and means for swinging the delivery member relative to the elbow, comprising a rack carried by the elbow, and a pinion carried by the delivery member and adapted to travel up and down the rack, and means 120 for rotating the pinion.

5. In a trimmer adapted to be supported at the bottom of a delivery chute for distributing material in the hatch of a boat, an elbow adapted to be rotated about the 125

- axis of the chute, a delivery member hinged to said elbow and provided with a conveyor, a motor supported by the delivery member and connected to the conveyor to operate 5 the same, and mechanism for connecting the motor to the elbow for swinging the delivery member relative thereto, said mechanism comprising a rack and pinion, one adapted to move relative to the other, and one carried by the elbow and the other by the delivery member, and means for actuating one of said members by the motor.
6. A trimmer for distributing material in 15 the hatch of a boat comprising a rotatable elbow provided with a curved bottom and rear wall, a curved rack carried by the elbow, a delivery member hinged to swing vertically relative to the elbow and carrying a pinion adapted to travel up and down said 20 curved rack, and means for rotating the pinion to swing the delivery member relative to the elbow.
7. In a trimmer adapted to be attached to the lower end of a delivery chute for 25 distributing material in the hatch of a boat and comprising an elbow adapted to be rotated about the axis of the chute, and provided with a curved bottom and rear wall, a curved rack carried by the elbow, a delivery member hinged to swing vertically relative to the elbow and carrying a pinion adapted to travel up and down said curved 30 rack, and motor driven mechanism for rotating the pinion.
8. In a trimmer adapted to be attached to the lower end of a delivery chute for 35 distributing material in the hatch of a boat and comprising an elbow adapted to be rotated about the axis of the chute, and provided 40 with a curved bottom and rear wall, a curved rack carried by the elbow, a delivery member hinged to swing vertically relative to the elbow, mechanism carried by the delivery member for swinging the delivery member 45 relative to the elbow, and comprising a shaft at the rear of the curved wall of the elbow, a pinion on the shaft engaging said rack, and means for rotating said shaft comprising self-locking gearing.
9. In a trimmer adapted to be attached to the lower end of a delivery chute for 50 distributing material in the hatch of a boat and comprising an elbow adapted to be rotated about the axis of the chute, and provided 55 with a curved bottom and rear wall, a curved rack carried by the elbow, a delivery member hinged to swing vertically relative to the elbow, mechanism carried by the delivery member for swinging the delivery member 60 relative to the elbow and comprising a shaft at the rear of the curved wall of the elbow, a pinion on the shaft engaging said rack, a motor, and means connecting the motor to said shaft.
10. In a trimmer adapted to be attached to the lower end of a delivery chute for distributing material in the hatch of a boat and comprising an elbow adapted to be rotated about the axis of the chute, and provided 65 with a curved bottom and rear wall, a curved rack carried by the elbow, a delivery member hinged to swing vertically relative to the elbow, mechanism carried by the delivery member for swinging the delivery member relative to the elbow, and comprising a shaft 70 at the rear of the curved wall of the elbow, a pinion on the shaft engaging said rack, a motor, and means connecting the motor to said shaft, said delivery member having a conveyor, and a driving connection between 75 said motor and the conveyor to operate the same.
11. In a trimmer for a boat loading apparatus, an elbow adapted to be supported at the lower end of a member for delivering material to the trimmer, a swinging delivery member rotatably supported with reference to the elbow, motor driven mechanism for swinging the delivery member, and means for automatically stopping the swinging 80 movement when the delivery member reaches a certain position.
12. In a trimmer, an elbow, a delivery member pivotally supported relative thereto so that it may be swung vertically to vary 85 the angle of discharge, motor driven mechanism for swinging the delivery member, and means for automatically stopping the swinging 90 movement when the delivery member is swung to either extreme position.
13. A trimmer comprising a member adapted to be supported at the lower end of a delivery chute, a delivery member pivoted thereto, mechanism for swinging the delivery member relative to the first-named member and comprising a motor, power transmitting mechanism having a clutch, and means for automatically throwing out the clutch when the delivery member 95 is swung to a certain position.
14. A trimmer comprising a member adapted to be supported at the lower end of a delivery chute, a delivery member pivoted thereto, mechanism for swinging the delivery member relative to the first-named member and comprising a motor, power transmitting mechanism having a clutch, and means for automatically throwing out the clutch when the delivery member is swung to a given position in either direction.
15. A trimmer for a boat loading apparatus comprising an elbow, a delivery member pivotally mounted relative thereto to be swung vertically, said delivery member comprising guide walls and carrying a conveyor including a pair of drums, and a delivery belt extending about the drums and having its top leg extending between the 120

guide walls, the delivery member opposite the belt being open for the removal of the belt from the drums in a lateral direction.

16. A trimmer for a boat loading apparatus comprising a rotatable elbow, a delivery member pivotally supported relative thereto and adapted to be swung vertically to vary the angle of discharge, said delivery member comprising a pair of guide walls 10 and carrying a conveyor including a pair of drums and a delivery belt passing about the drums and having its top leg extending across the space between the guide walls, the lower edges of the guide walls being close to 15 but above the top leg of the belt and the belt being removable laterally from the drums beneath the guide walls.

17. A trimmer for a boat loading appa-

ratus comprising a rotary elbow and a delivery member pivoted to swing vertically 20 relative thereto so as to vary the angle of discharge, said delivery member comprising a lower structure, a pair of upper guide walls for guiding the material being delivered, and a belt rotatably supported on said 25 lower structure below the guide walls and having its upper leg extending between the guide walls below but close to the same, the delivery member opposite the belt between the guide walls and said lower structure being open whereby the belt may be removed 30 from the delivery member laterally thereof.

In testimony whereof, I hereunto affix my signature.

ARTHUR F. CASE.
